UNITED STATES PATENT OFFICE.

JOHN SPARENBURG, OF CHICAGO, ILLINOIS.

SHAMPOOING DEVICE.

1,083,707.

Specification of Letters Patent.

Patented Jan. 6, 1914.

Application filed May 31, 1913. Serial No. 771,067.

To all whom it may concern:

Be it known that I, JOHN SPARENBURG, a citizen of the United States, and a resident of the city of Chicago, county of Cook, and 5 State of Illinois, have invented certain new and useful Improvements in Shampooing Devices, of which the following is a specification.

My invention relates to shampooing devices, and the object of the improvement is 10 to provide a device of the character mentioned which is of simple construction and efficient in operation.

The invention consists in the combinations 15 and arrangements of parts hereinafter described and claimed.

The invention will be best understood by reference to the accompanying drawing forming a part of this specification, and in 20 which—

Figure 1 is side elevation of a device embodying my invention, Fig. 2 is a plan view of the shampoo tray showing the connection with its supporting spider, and Fig. 3 is a 25 section taken on line 3—3 in Fig. 1.

The preferred form of construction as illustrated in the accompanying drawing comprises a hollow upright 4 having supporting legs 5 at its bottom and provided 30 with a thumb screw 6 near its top. Mounted in the upright 4 is a post 7 which is adapted to be moved upwardly and downwardly therein and locked in such different positions by means of thumb screw 6.

Carried near the top of post 7 is a laterally extending arm 8 and pivoted at the top of said post 7 is a spider 9 which supports the shampoo tray 10. The shampoo tray 10 is provided with a plurality of ears 11 secured to the under side thereof by means of solder, or its equivalent, in a manner to 35 present a smooth unpunctured surface on the inside of said tray. The arms of spider 9 engage in the ears 11 substantially as indicated and are removably secured thereto by means of screws 12, or their equivalent.

Pivotedly connected to one end of spider 12 is a connecting link 13 and said connecting link is provided with a slot 14 at its

other end which is adjustably secured on 50 arm 8 by means of a locking pin 15. Said locking pin 15 is of thumb-screw design in order to facilitate adjustment of the link 13 on arm 8. In operation, the device is placed between the person having his hair 55 shampooed and a waste basin, not shown, or some other means of receiving water from the end 16 of the shampoo tray 10. The recess 17 formed in one side of the tray is designed to fit about the neck of the 60 person having his hair shampooed or washed and the tray 10 placed at a convenient angle to allow the water to run from the open end 16 of said tray. The tray 10 is designed to hold the hair of a person during the process 65 of shampooing or washing. The device for locking the tray at different angles of inclination and the supporting stand are of rigid construction affording a substantial device for the purpose mentioned. 70

While I have illustrated and described the preferred form of construction for carrying my invention into effect, this is capable of variation and modification without departing from the spirit of the invention. I, 75 therefore, do not wish to be limited to the precise details of construction set forth, but desire to avail myself of such variations and modifications as come within the scope of the appended claims. 80

Having described my invention what I claim as new and desire to secure by Letters Patent is:

1. A device of the kind described comprising an adjustable stand; a spider pivoted on said stand; a shampoo tray removably secured to said spider; and a connecting link pivotally connected with said spider and having a slot and pin connection with said stand, substantially as described. 85 90

2. A device of the kind described comprising an adjustable stand; a spider on said stand; ears removably secured to said spider; a shampoo tray secured to said ears; and an adjustable lock locking said spider 95 in different inclined positions, substantially as described.

3. A device of the kind described compris-

ing an adjustable stand; a spider on said stand; ears removably secured to said spider; a shampoo tray secured to said ears; an arm on said stand; a link having one end pivoted to said spider and provided with a slot at its other end; and a locking pin in said slot and threaded in said arm, substantially as described.

In testimony whereof I have signed my name to this specification in the presence of 10 two subscribing witnesses.

J. SPARENBURG.
